ILLUMINATED CURBING NOSE SECTION

Wilfried Baatz, Bellevue, Wash., assignor to Traffic & Safety Control Systems, Inc., Seattle, Wash.

Filed June 8, 1970, Ser. No. 23,375

Term of patent 14 years

Int. Cl. D25—99; D26—99

U.S. Cl. D60—1

FIG. 1.

FIG. 2.

FIG. 3.

FIG. 4.

FIG. 5.

FIG. 1 is an isometric view of an illuminated curbing nose section, showing the new design.

FIGS. 2, 3, 4 and 5 are top, front, side and back views, respectively, of the illuminated curbing nose section of FIG. 1.

I claim:

The ornamental design for an illuminated curbing nose section, as shown and described.
